FIG. 1 is a bottom plan view of a handle for a holder for a safety razor blade showing my new design, the holder being shown in broken lines;

FIG. 2 is a top plan view thereof;

FIG. 3 is a right side elevational view thereof, the left side being a mirror image thereof;

FIG. 4 is a front elevational view thereof;

FIG. 5 is a rear elevational view thereof;

FIG. 6 is a sectional view taken along the line 6—6 of FIG. 1; and,

FIG. 7 is a sectional view taken along the line 7—7 of FIG. 2.

The elements shown in broken lines are for illustrative purposes only and form no part of the claimed design.
